UNITED STATES PATENT OFFICE.

SARA MAY ALLINGTON, OF ELMIRA, NEW YORK.

DESIGN FOR A TOY AERIAL FLIGHT.

No. 37,685.

Specification for Design.

Patented Nov. 21, 1905.

Application filed October 7, 1905. Serial No. 281,869. Term of patent 7 years.

To all whom it may concern.

Be it known that I, SARA MAY ALLINGTON, a citizen of the United States, residing at Elmira, in the county of Chemung and State of New York, have invented a new, original, and ornamental Design for a Toy Aerial Flight, of which the following is the specification, reference being had to the accompanying drawings, forming part thereof.

Figure 1 is a perspective view of a toy aerial

flight constructed in accordance with my new design. Fig. 2 is a top plan view thereof.

I claim—

The ornamental design for a toy aerial flight, as shown.

SARA MAY ALLINGTON.
